(57) **CLAIM**

The ornamental design for a cheek retractor device, as shown and described.

DESCRIPTION

The disclosure of U.S. Design patent application Ser. No. 29/532,890, filed Jul. 10, 2015, entitled Cheek Retractor Device, and PCT application PCT/US2014/028083, filed Mar. 14, 2014, are each incorporated by reference in their entirety.

FIG. 1 is a front perspective view of a cheek retractor device according to the present invention;

FIG. 2 is a rear perspective view of the cheek retractor device of FIG. 1;

FIG. 3 is a front view of the cheek retractor device of FIG. 1; FIG. 4 is a rear view of the cheek retractor device of FIG. 1; FIG. 5 is a first side view of the cheek retractor device of FIG. 1;

FIG. 6 is an opposite side view of the cheek retractor device of FIG. 1;

FIG. 7 is a top view of the cheek retractor device of FIG. 1; and,

FIG. 8 is a bottom view of the cheek retractor device of FIG. 1.

The cheek retractor device is shown with a symbolic break in its length. The appearance of any portion of the article between the break lines forms no part of the claimed design. The broken lines shown in FIGS. 1-8 illustrate portions of the cheek retractor device that form no part of the claimed design.
